LOUD SPEAKER UNIT

Filed July 2, 1928

UNITED STATES PATENT OFFICE

MATTHEW K. KUCHINSKY, OF NEWARK, NEW JERSEY

LOUD-SPEAKER UNIT

Application filed July 2, 1928. Serial No. 289,984.

This invention relates to driving units for use in connection with loud speakers, and comprises a device for transforming variable electric currents into mechanical impulses suitable for the actuation of a diaphragm or other similar device for changing these mechanical impulses into sound waves.

It is a general object of the present invention to provide a novel and improved form of loud speaker unit.

More particularly one of the features of the invention comprises a novel means of providing for the adjustment of the air gap between the pole faces of the magnet.

Another feature consists in the arrangement of pole pieces to produce a pair of unidirectional parallel magnetic fields to cooperate with an armature extending between the fields and provided with means for polarizing the same, together with unique means for adjusting the strength of one of the pair of magnetic fields to be equal to that of the other to compensate for the difference in distance of the pole tips from the main poles of the magnet.

Another feature of the invention comprises a novel mounting for the armature and its flexible support.

A further feature of the invention comprises the arrangement of a pair of members adapted to be secured to the opposite edges of the poles of the magnet and to carry the armature supporting means and the armature polarizing means together with novel means for adjusting this assembly to obtain maximum efficiency.

Still another feature of the invention comprises the arrangement of adjusting means between the arms of the horseshoe magnet, said means supporting a terminal block and a fulcrum for the multiplying lever.

Other and further features and objects of the invention will be more apparent to those skilled in the art upon a consideration of the accompanying drawing and the following specification, wherein is disclosed a single exemplary embodiment of the invention with the understanding, however, that various changes may be made therein such as fall within the scope of the appended claims with-

out departing from the spirit of the invention.

In said drawings:

Figure 1 is a side elevation of the loud speaker unit showing the same arranged to operate a cone-shaped diaphragm;

Figure 2 is a plan view of the same looking at the end of the magnet;

Figure 3 is a vertical section on line 3—3 of Fig. 2;

Figure 4 is a vertical section at right angles to that of Fig. 3 and taken on line 4—4 of Fig. 1; and

Figure 5 is a perspective view of the armature and its supporting means.

The present invention contemplates the provision of an extremely simple loud speaker unit and one which can be assembled readily for large scale production and, while being cheap to produce, is yet effective in the accurate reproduction of sounds received by it in electrical form.

The unit as disclosed in the drawings includes the horseshoe or U-shaped magnet 10 either permanent or electrically excited, having the substantially parallel arms 11, 12, which are rectangular in cross section as best seen in Fig. 2. The tips of these arms are cut off square as shown in the drawing, and just below the ends have attached to their inner faces the pole piece supporting blocks 13 of non-magnetic and preferably of insulating material. These blocks are rigidly attached to the inner faces of the arms 11, 12 by means of screws 14.

Since it is desired to provide a pair of unidirectional parallel magnetic fields, it is necessary that each arm of the magnet carries a pair of pole pieces. This is contrived by mounting the pole pieces on the upper and lower surfaces of the pole piece supporting blocks 13, as best shown in Fig. 3. Thus, the lower face of each block 13 has secured thereto a pole piece 15, having its rear face 16 tightly abutting against the inner face of the arm of the magnet. The pole pieces are formed of blocks of magnetic material of the same width as that of the arms of the magnet. As shown in Fig. 2, each tapers to the narrow tip 17 which cooperates with the armature

later to be described. They are likewise chamfered on their outer faces as shown at 18 to reduce the area of the actual pole tip to quite a smaller size to thus concentrate the magnet flux.

- 5 The upper pole pieces 19 are identical in shape with the lower pole pieces but are slightly shorter in order to provide an air gap 20 between their rear faces and the inner faces of the corresponding magnet arms. 10 Each pole piece is secured to its respective block 13 by means of two screws, those securing the lower pole pieces and numbered 21 passing through closely fitting openings in these pole pieces to insure that they fit with their faces 16 against the magnet arms. 15 The screws 22 for the upper pole pieces, however, pass through elongated slots 23 in these pole pieces in order that adjustment may be 20 effected to vary the air gaps 20.
- 20 Since an armature is balanced with its opposite ends between the upper pole tips and the lower pole tips and since these ends are equally polarized, it is highly desirable that 25 the magnetic fields at the opposite ends of the armature be of the same intensity. It is well-known that the magnetic field at the very tips of a U-shaped magnet is more intense than at any other place. If, therefore, 30 the pole pieces 15 and 19 were both abutted against the inner faces of the magnet arms, the intensity of the field between the pole pieces 19 would be greater than that between the pole pieces 15. However, by providing the 35 adjustable air gaps 20, the pole pieces 19 can be adjusted to exactly compensate for the greater intensity of magnetic lines at the tip of the U-shaped magnet so that a pair of unidirectional parallel magnetic fields of equal 40 intensity are provided by the present arrangement.

- In order to jointly adjust the distance between the tips of the two sets of pole pieces to equally change their action on the armature end, means are provided for drawing together or separating the arms of the magnet. This means comprises a sleeve 25 of non-magnetic material internally threaded and secured to the arm 12 by means of the screw 45 26 passing through that arm. A screw 27 passes through the arm 11 and engages in the threads in the sleeve 25. It is provided with lock nuts 28 and 29 abutting respectively against the inner face of the arm 11 and the outer end of the sleeve 25 so that by proper manipulation of the screw 27 and the lock nuts, the arms of the horseshoe magnet may be drawn together or be separated as desired 50 to adjust the gap between the tips of the pole pieces previously described.

The armature which is adapted to be balanced between the pole tips comprises a rectangular block 30 of suitable magnetic material having a length about equal to the vertical height between the outer faces of the

pole tips and a width about equivalent to the width of the tips 17. This armature 30 is carried and flexibly positioned by means of the armature supporting spring plate 31 formed of suitable non-magnetic spring material, such as phosphor-bronze. The plate 31 is shaped like a pair of truncated triangles, the truncated ends of which are attached to the center of the armature preferably by being swaged into slits therein with 70 the armature at right angles to the plane of the plate. The assembled armature and spring is best shown in Fig. 5.

The ends of the spring plate are each provided with a pair of spaced longitudinal parallel slits 32, and the three tongues thus formed are bent back over the plate as shown in Fig. 5, the center one in one direction and the end ones in the other to form the curved supporting members 33 and 34. The distance between the ends of the plate as defined by the parts 33 and 34 is slightly greater than the width of the arms 11 and 12 of the magnet. The armature spring plate is attached to the supporting plates 35 best seen in Fig. 90 1. These plates are of suitable non-magnetic material, and they are arranged to extend over the edges of the arms of the magnet and to be secured against the ends of the non-magnet blocks 13 by suitable securing means, such as the screws 36, one at each end of each plate. One plate is fastened on either side to the magnet centrally between the upper and lower pole pieces, as shown in Figs. 2 and 4. Each plate 35 is provided with a longitudinal depression 38 of a length slightly greater than the width of the base of the armature spring plate, and into this depression, which is curved to conveniently fit the parts 33 and 34, these parts are arranged and 95 suitably secured as by solder as shown at 40. This rigidly and permanently secures the ends of the spring plate to the supporting plates and insures that, when the plates are secured in position by means of the screws 36, the armature will be permanently positioned where desired. The position of the armature is adjustable since the openings 37 in the supporting plates through which the screws 36 pass are larger than the screws, allowing the 100 plates 35 to be slightly manipulated to exactly centralize the armature between the pole tips both laterally and longitudinally.

The coils for polarizing the armature and which are excited by the current from a suitably modulated source are connected in series and arranged one about each end of the armature and in parallel planes. Each coil 42 is in the form of a perforated flat disk substantially rectangular with rounded corners, as shown best in Fig. 2. In reality the coils are wound on spools of non-conducting material having the cheeks 43 which define the outline of the coil assembly. The thickness of each coil between the outer faces of 105 110 115 120 125 130

the cheeks 43 is such as to cause it to fit tightly between the inner face of one set of pole pieces and the projecting ends of the tongues 33 or 34 on the armature spring plate, as 5 clearly shown in Fig. 4. Thus, each coil is pressed against its corresponding pole pieces and held accurately spaced away from the armature spring plate. The longer edges of the cheeks of the coils engage the inner 10 faces of the non-conducting blocks 13 secured to the arms of the magnet, and the shorter edges of these cheeks engage against the flat inner surfaces of the armature assembly supporting plates 35. The coils are thus rigidly 15 positioned against movement in any direction, and each surrounds one end of the armature.

In order to provide a rigid terminal block or board to which are secured the leads from 20 the coils, a suitable sheet of insulating material, such as fibre, is cut to the form shown at 45 and is drilled to be received over the screw 27 on the magnet arm adjuster so that it can be clamped between the end of the 25 sleeve 25 and the lock nut 29 and held in the position best shown in Fig. 4. The terminals 46 are bolted through this sheet and receive the lugs 47' under the nuts 48'. To these lugs are soldered the ends of the wires 30 49' leading from the coils. This provides a rigid and permanent terminal board which is not subject to rattling under violent action of the armature.

Movement of the armature is adapted to be 35 transmitted to the diaphragm through a link 47 and multiplying lever 48. This lever, which may be of light rigid material, is suitably fulcrumed at one end and at the opposite end 49 is attached to the rod 50 which may be 40 connected to any suitable form of diaphragm, here shown as a cone 51. The lower end of the lever 48 is preferably secured to a thin spring 52 which is drilled to be received over the screw 26 which holds the sleeve 25 in position 45 against the magnet arm 12. A spacer washer fits between the magnet arm and the spring 52 as shown. The link 47 is connected at one end to the lug 53 on the upper end of the armature and at the other end by means 50 of a suitable spring or pivot 54 to the lever 48 intermediate its ends.

The device just described is extremely simple to manufacture and is readily assembled and adjusted. It is rigid in its construction, insuring against parasitic vibrations and noises, and provides a compact arrangement of an efficient and effective power unit for driving diaphragms of loud speakers.

Having thus described the invention, what is claimed as new and desired to be secured by Letters Patent is:

1. In a loud speaker, in combination, a magnet having substantially parallel arms, a 53 pair of cooperating pole pieces associated

with said arms, a second pair of cooperating pole pieces associated with said arms, one pair of pole pieces being in a region of greater flux from said magnet than the other, and means to adjust the flux distribution to equalize it through the two pairs of pole pieces. 70

2. In a loud speaker, in combination, a magnet having a pair of arms with facing surfaces, a pole piece supporting block secured to each face, a pole piece secured to 75 each block near the ends of the magnet arms, a pole piece secured to each block at a distance from the ends of said arms and in engagement therewith, each set of pole pieces being adapted to cooperate with one end 80 of a balanced armature, said first set of pole pieces being spaced from said arms, to reduce the flux therethrough to substantially that through the second set.

3. In a loud speaker, in combination, a 85 magnet having a pair of arms of opposite polarity, two pole pieces for each arm spaced different distances from the tip thereof, those of the same distance on opposite arms forming cooperating pairs, the pieces of one pair 90 being in closer magnetic relation to the arms than the other for the purpose described.

4. In a loud speaker, in combination, an armature, an elongated spring extending transverse to and from the center of said armature, a coil surrounding each end of said armature and parallel to said spring, and lugs on the ends of said spring to space said coils therefrom. 95

5. In a loud speaker, in combination, an 100 armature, an elongated spring extending transverse to and from the center of said armature, the ends of said spring being divided with portions thereof turned back over the spring on each side thereof. 105

6. In a loud speaker, in combination, an armature, an elongated spring extending transverse to and from the center of said armature, the ends of said spring being divided with portions thereof turned back over the 110 spring on each side thereof, a supporting plate secured to each end of said spring and a coil surrounding each end of said armature, each coil engaging both supporting plates and being spaced from said spring by 115 said turned back ends thereof.

7. In a loud speaker, in combination, an armature, an elongated spring extending transverse to and from the center of said armature, the ends of said spring being divided with portions thereof turned back over the 120 spring on each side thereof, supporting plates each having a groove to receive the turned back ends of said spring, and means securing said ends in said grooves with portions of the turned back ends projecting out of said grooves on each side of the spring. 125

8. In a loud speaker, in combination, an armature, an elongated spring extending transverse to and from the center of said ar- 130

mature, the ends of said spring being divided with portions thereof turned back over the spring on each side thereof, a supporting plate secured to each end of said spring, a 5 coil surrounding each end of said armature, each coil engaging both supporting plates and being spaced from said spring by said turned back ends thereof, and pairs of pole pieces cooperating with the ends of said armature beyond said coils, said pole pieces 10 engaging the outer faces of said coils.

9. In a loud speaker, in combination, an armature, an elongated spring extending transverse to and from the center of said armature, the ends of said spring being divided with portions thereof turned back over the spring on each side thereof, a supporting plate secured to each end of said spring, a 15 coil surrounding each end of said armature, each coil engaging both supporting plates and being spaced from said spring by said turned back ends thereof, pairs of pole pieces cooperating with the ends of said armature beyond said coils, said pole pieces 20 engaging the outer faces of said coils, and means between the pairs of pole pieces engaging the edges of said coils whereby they are prevented from moving in any direction.

10. In a loud speaker, in combination, an armature, an elongated spring extending transverse to and from the center of said armature, the ends of said spring being divided with portions thereof turned back over the spring on each side thereof, a supporting 30 plate secured to each end of said spring, a coil surrounding each end of said armature, each coil engaging both supporting plates and being spaced from said spring by said turned back ends thereof, pairs of pole pieces 35 cooperating with the ends of said armature beyond said coils, said pole pieces engaging the outer faces of said coils, and means between the pairs of pole pieces engaging the edges of said coils whereby they are prevented from moving in any direction, the 40 said supporting plates being secured to said means.

In testimony whereof I hereunto affix my signature.

50 MATTHEW K. KUCHINSKY.
